UNITED STATES PATENT OFFICE.

JOHN H. WHISLER, OF BROADWAY, VIRGINIA.

IRONING-BOARD AND STEP-LADDER.

SPECIFICATION forming part of Letters Patent No. 398,297, dated February 19, 1889.

Application filed July 21, 1888. Serial No. 280,623. (No model.)

To all whom it may concern:

Be it known that I, JOHN H. WHISLER, of Broadway, in the county of Rockingham and State of Virginia, have invented certain new 5 and useful Improvements in a Combined Ironing-Board and Step-Ladder; and I do hereby declare the following to be a full, clear, and exact description of the invention, such as will enable others skilled in the art to which 10 it pertains to make and use it, reference being had to the accompanying drawings, which form part of this specification.

My invention relates to an improvement in a combined ironing - board and step-ladder; 15 and it consists in the combination of the legs or supports, which are united together in pairs by cross-bars which have their ends project beyond the sides of the legs to form stops, side bars between which the pairs of legs are 20 pivoted, the ironing-board loosely connected to one of the pairs of legs, hooks to brace the legs to the side bars, a brace-rod loosely connected to the board at one end, and eyes in which the hooked end of the brace-rod catches, 25 as will be more fully described hereinafter.

The objects of my invention are to combine an ironing-board and a step-ladder in a single 30 implement and to connect the legs or supports together by means of the side bars, in between 35 which the ironing-board and supports will snugly fold when closed, and thus take up very little room.

Figure 1 is a side elevation of a device which embodies my invention complete, the parts 35 being so arranged as to form an ironing-board. Fig. 2 is an end view of the same. Fig. 3 is a side elevation of a device arranged so as to form a step-ladder. Fig. 4 is a plan view showing the parts folded together.

40 A represents the legs or supports, which are connected together in pairs by means of the cross-bars or rungs B, the two lower ones of which project at their ends a suitable distance beyond the sides of the legs, so as to form 45 stops C, which catch against the under edges of the cross-bars D, by means of which the legs or supports are joined together in pairs, and thus limit the movement of the legs. The rear legs are joined together at their upper 50 ends by means of the cleat E, which extends

across under the end of the ironing-board F, and which has pivots G formed upon its ends to pass through suitable openings prepared to receive them in the upper ends of the legs. The front pair of legs are united together at 55 their upper ends by the cross-bar G', which does not form one of the rungs of the ladder, because it rests upon the floor while the implement is being used as a ladder, and which is provided for the purpose not only of bracing the upper ends of these two legs together, but for forming a cross-bar under which the revolving button H on the under side of the ironing-board F is made to catch for the purpose of locking the front end of the board in 60 position. Secured to each pair of legs is a hook, I, which, when the parts are being used as an ironing-board, have their lower ends catch in holes made in one of the side bars, D, and thus lock the parts rigidly in position. 65 The side bars, D, serve not only to connect the legs together in pairs, but as fulera in which the legs or supports turn, both when the parts are being closed together, as shown in Fig. 4, and when being arranged to form a ladder, as 70 shown in Fig. 3. The ends of the cross-bars B form stops C, so as to limit the angle at which the legs A shall be set in forming a support for the ironing-table by striking against the under edges of the side bars, D, and to 75 limit the distance that the legs A shall move inside of the cross-bars D when the legs are folded in a line therewith, either for the purpose of forming a step-ladder or when the parts are folded together to be packed away 80 or for transportation.

When the parts are being used for an ironing-board, the legs are locked in position in relation to the side bars, D, by means of the hooks I, and the ironing-board is locked by 85 the button H.

The iron brace J, which is secured to the under side of the board F, passes through the loop or staple O, secured to one of the cross-bars B of the rear legs or supports A, but 90 without engaging therewith. If the front end of the board is to be raised upward, so that a garment can be passed over it, the button H is loosened and the front end of the board is raised upward until the hooked end of the 95 100

brace J engages with the staple O, when the front end of the board will be held in a raised position.

- When the parts are to be used as a step-ladder, the hooks I have their ends loosened from the bars D, the legs or supports A are folded up inside of the bars D, the ironing-board F is set at a suitable angle, so as to form a brace or support for the ladder, and the rod J is made to hook in an eye or staple, P, secured to the inner side of one of the side bars, D. To hold the ladder and the board rigidly in relation to each other when the legs or supports are folded inside of the side bars, the stops C strike against the outer edges of the bars and prevent the weight of the person upon the ladder from forcing the legs or supports through the bars, to which they are only pivoted.
- When my invention is no longer needed for immediate use, the legs or supports are folded inside of the side pieces from one side and the board folded inside of the legs and the side pieces from opposite sides, so that the

parts only take up the thickness of the side bars, B, and cross-bars D.

The parts are light, cheap, and durable, and, as they can be converted either into a step-ladder or an ironing-board, are a great convenience.

Having thus described my invention, I claim—

The combination of the legs or supports A, the cross-pieces B, which project at their ends beyond the sides of the legs, the side bars, 35 between which the legs or supports are pivoted, the ironing-board pivoted at one end between one of the pair of legs, the hooks I, the brace-rod fastened to the board at one end and hooked at the other, and the eyes in 40 which the hook catches, substantially as shown.

In testimony whereof I affix my signature in presence of two witnesses.

JOHN H. WHISLER.
